CASING FOR AN ELECTRIC SHAVER

Raymond A. Somers, Fairfield, Conn., assignor to Sperry Rand Corp., New York, N. Y., a corporation of Delaware

Application November 29, 1956, Serial No. 43,988

Term of patent 7 years

(Cl. D22—3)

FIG. 2.

FIG. 1.

FIG. 3.

FIG. 4.

Fig. 1 is a front elevation of a casing for an electric shaver showing my new design, the back thereof being similar in appearance;

Fig. 2 is a top plan view thereof;

Fig. 3 is a side elevation thereof, the opposite side being similar in appearance; and

Fig. 4 is a bottom plan view thereof.

I claim:

The ornamental design for a casing for an electric shaver, as shown and described.
